DENTAL CONSOLE

Frank I. Fuller, Portola Valley, Calif., Shirl S. Fox, 45
Cerros Manor, Menlo Park, Calif. 94025, and Ronald
F. Keller, Aptos, Calif.; said Fuller and said Keller
assignors to said Fox

Filed Dec. 31, 1969, Ser. No. 20,712

Term of patent 14 years

Int. Cl. D24—03

U.S. Cl. D24—1

Fig. 6

Fig. 7

FIG. 1 is a front elevational view of a dental console incorporating our new design;

FIG. 2 is a rear elevational view of the same;

FIG. 3 is a side elevational view of the same as viewed from the left from the illustration shown in FIG. 1;

FIG. 4 is a side elevational view thereof viewing the same from the right as illustrated in FIG. 1;

FIG. 5 is a top plan view thereof;

FIG. 6 is a perspective view as seen from the top and front from the illustration shown in FIG. 1; and

FIG. 7 is a perspective view as seen from the bottom and rear of the illustration shown in FIG. 1.

We claim:

The ornamental design for a dental console, as shown.
